DISPENSING AND DISPLAY CARTON

Max Goldberg, Chicago, Ill., assignor to National Soda Straw Company, Chicago, Ill., a corporation of Illinois

Application November 15, 1934, Serial No. 753,100

8 Claims. (Cl. 229—17)

My invention relates to an improved dispensing and display carton, and the blank for forming it. The embodiment illustrated is particularly adapted for packaging soda straws, but the invention is equally valuable for use with many other articles.

Heretofore soda straws have generally been dispensed at fountains and elsewhere by first removing them from the carton in which they are packed and then placing them in a metal or glass dispenser on the counter, table or fountain, from which the customers help themselves. This way of dispensing straws is not entirely satisfactory because the straws must be handled to place them in the dispensers, and the cost of the dispensers is a considerable expense to the merchant.

My improved carton overcomes these objections because it not only provides a container for the straws but also serves as a dispenser so that the straws are not touched until the customer takes one for his drink. My carton is designed and finished so that it is ornamental as well as useful on the fountain or table.

In the accompanying drawing, I have illustrated one form that my invention may take, wherein:

Fig. 1 is a perspective view of my improved carton as it reaches the merchant filled with straws.

Fig. 2 is a perspective view of the top of the box showing how the straws may be removed.

Fig. 3 is a plan view of the top end of the carton with the top cover removed.

Fig. 4 is the blank from which the carton is formed.

Referring first to Fig. 4, the blank is cut and scored to form front, rear and side panels 5, 6, 7, 8. The front panel is ornamented by a window of fanciful design formed by cut out portions 9, 10, and a transparent covering 11 made from Cellophane or like material which preferably is glued inside the carton over both openings 9, 10. At the top, the front panel is cut away at 12 to provide a dispensing opening and at the bottom has a locking flap 13 carrying a locking tongue 14.

The rear panel 6 has a glue flap 15 along one edge and at its lower edge has a locking flap 16 with slots 17 that cooperate with the tongue 14 on the flap 13 to close the bottom of the carton. The top panel or lid 18 is connected along a score line 19 to the top of the rear panel 6 and at its free end has a tucking flap or tuck 20. A removable portion 21 is defined by a perforated or cut-score line 22 preferably partly on the tuck 20 and partly on the top 18. The removable portion 21

is here shown as circular but it may be of any desired shape and may be formed wholly on the top 18 in some instances.

At their lower ends, the side panels 7, 8 have end flaps 23, 24 which are folded in under the locking flaps 16, 17 to close the bottom of the carton. At the top are inner or locking flaps 25, 26 which are secured together under the top 18, as by the cooperating tongue 27 and slit 28. The flaps 25, 26 are cut away or have cut-outs at 29, 30 along lines corresponding to the removable portion 21 in the top, the edges 31, 32 of the cut-away portions meeting the edges of the cut-out 12 in the front panel and forming a continuation thereof when the blank is formed into the carton. The window 9, 10 may be of any design and of course is not limited to the front panel but may be provided in any or all of the four sides of the carton but is most effective in displaying the straws when it is in alignment with the dispensing opening 21, as shown in Fig. 1.

Fig. 1 shows the carton formed from the blank of Fig. 4 and filled with straws 33 which are visible through the window 11. The tuck 20 lies within the front side of the carton and it may be glued thereto in some cases but usually is only tucked in so that the entire top of the carton can be opened if desired, altho the carton is intended to be opened as shown in Fig. 2. The section 21 is torn out along the readily fracturable line 22 which provides a dispensing opening in the top 18 and tuck 20 that registers with the edges of the cut-outs 12, 29, 30 in the front 5 and flaps 25, 26. The carton is then placed on the counter or table and the customers withdraw the straws 33, one at a time, through the opening as they are needed. The carton not only makes an attractive display and also avoids handling of the straws except as they are used by the customers.

The vertical sides or panels 5, 6, 7, 8 and the completed carton are much greater in height than in width and this is necessarily so, otherwise the straws would fall over whenever the carton was partly empty so that they could not be reached through the dispensing opening. In other words, the lateral dimensions of the carton must be small enough in relation to the height, that the straws will stand vertically or substantially so until the last one is withdrawn.

While I have shown my carton as adapted for dispensing soda straws, it is equally useful with many kinds of merchandise such as cigarettes, matches, and other articles desired to be used or dispensed one at a time.

Having thus described one form that my inven-

tion may take, I claim all modifications and equivalents thereof that may come within the following claims.

I claim:

- 5 1. A carton having a front wall with a cut-away portion at its upper edge, a rear wall having a top hinged thereto along one edge, the opposite edge of said top having a tuck lying within said front wall, there being a potential dispensing opening defined by a fracturable line partly on said top and partly on said tuck, the part on said tuck conforming with the cut-away portion on said front wall.
- 10 2. A carton having front, rear and side walls, the front wall having a cut-away portion at its upper edge, locking flaps hinged to the tops of said sides and interlocking at the top of the carton, said flaps having cut-away portions joining the cut-away portion in said front wall and forming a continuation thereof, a top hinged at one side to the top of the rear wall and at its opposite side having a tuck lying within said front wall, there being a dispensing opening in said top and tuck overlying the cut-away portions of said front wall and locking flaps.
- 15 3. A carton having four side walls, the front wall having a cut-away portion at its upper edge, the rear wall having a top hinged thereto at one edge and at its opposite edge having a tuck lying within the front wall, said top and tuck having a dispensing opening formed therein, that part of the opening in the tuck corresponding in contour to the cut-away portion in the front wall, at least one of said four walls having a display window.
- 20 4. A carton blank having formed thereon from end to end a side, a front, a second side and a rear panel and a glue flap, bottom closing flaps attached at the lower edges of said panels, a top panel connected to the top of the rear panel and having a tucking flap at one edge, there being a potential dispensing opening formed by a weakened line in said top panel and tucking flap, each side panel having a locking flap at its upper edge
- 25 with a cut-out portion corresponding in contour to a part of the potential dispensing opening in said top panel, said front panel having a cut-out portion in its upper edge corresponding in contour to the potential dispensing opening in said tucking flap.
- 30 5. A carton blank having formed thereon from end to end a side panel, a front panel, a second side panel, and a rear panel and a glue flap, bottom closing flaps attached at the lower edges of said panels, locking means for two of said

flaps, a top panel connected to the top of the rear panel and having a tucking flap at one edge, there being a potential dispensing opening formed by a weakened line in said top panel and tucking flap, each side panel having a locking flap at its upper edge with a cut-out portion corresponding in contour to the potential dispensing opening in said top panel, said front panel having a cut-out portion in its upper edge corresponding in contour to the potential dispensing opening in said tucking flap, one of said panels having a display window intermediate its ends.

6. A carton having front, rear and side walls, the front wall having a cut-away portion at its upper edge, locking flaps hinged to the tops of said sides and interlocking at the top of the carton, said flaps having cut-away portions joining the cut-away portion in said front wall and forming a continuation thereof, a top hinged at one side to the top of the rear wall and at its opposite side having a tuck lying within said front wall, there being a potential dispensing opening in said top and tuck defined by a weakened line overlying the cut-away portions of said front wall and locking flaps.

7. A carton having front, rear and side walls, a top hinged at one edge to the rear wall and at its opposite edge having a tuck lying within the said front wall, there being a removal section partly in said top and partly in said tuck defined by a readily fracturable line completely surrounding said section, that part of the top edge of the front wall being cut away over that part of the removable section that lies in the tuck whereby upon breaking said fracturable line and removing said section a dispensing opening is provided in said top and front wall.

8. A combined carton and dispenser for soda straws and the like comprising front, rear and side walls, the said walls being of greater height than width and adapted to hold the straws substantially vertical, inner flaps hinged to the tops of the side walls and overlapping at the end of the carton, a top hinged to the top of the rear wall and at its opposite side having a tuck lying within the front wall, there being a potential dispensing opening defined by a readily fracturable line partly on said top and partly on said tuck, said top overlying said inner flaps, said inner flaps and front wall being constructed and arranged to give access to the carton through the opening provided in said top and tuck upon breaking said readily fracturable line.

MAX GOLDBERG.
